C. H. BULLEN

APPARATUS FOR MAKING CONCRETE PIPE

Filed June 1, 1923

Inventor
Clare H. Bullen

by Attorney Thomas Blyne

UNITED STATES PATENT OFFICE.

CLARE H. BULLEN, OF PORTLAND, OREGON, ASSIGNOR TO TUERCK MACKENZIE MACHINE CO., OF PORTLAND, OREGON, A CORPORATION OF OREGON.

APPARATUS FOR MAKING CONCRETE PIPE.

Application filed June 1, 1923. Serial No. 642,728.

To all whom it may concern:

Be it known that I, CLARE H. BULLEN, a citizen of the United States, and a resident of the city of Portland, in the county of 5 Multnomah and State of Oregon, have invented certain new and useful Improvements in Apparatus for Making Concrete Pipe, of which the following is a specification.

This invention relates to improvements in 10 concrete pipe making machines.

The object of the present invention is the provision of a machine of the class described including a revolving table upon which the concrete pipe is molded having 15 improved and simple means for securing a mold thereto that may be quickly and readily adjusted to accommodate the various sizes of molds when a change of molds is made.

20 A further object of the invention is the provision of means to support a concrete pipe mold in spaced relation above a table with which the mold is revolved, the palette element of the mold being provided with 25 supporting legs so that accidental obstructions on the table will not affect the vertical alignment of the mold and when removed therefrom the green pipe will be maintained during the setting period upon a level support.

30 A still further object of the invention is the provision of devices for preventing the lodgement of cement material in the openings necessarily provided in the revolving table and accessories thereof.

35 A still further object of the invention is to provide means to compensate for any wear or distortion of the mold-base through continued use or accidental damage whereby 40 the mold walls may be aligned vertically and maintained concentric with the central core to ensure that the pipe walls will be symmetrical and of even thickness.

45 With the above and other objects in view, which will appear in the course of the succeeding specification, the invention consists in the novel construction of a concrete pipe making machine table, the mold and palette therefor, and the combination and adaptation therewith of novel means and devices for accomplishing the objects and advantages above set forth, and hereinafter explained, as will be fully described in the 50 following specification, illustrated in the

accompanying drawings, and finally pointed out in the appended claims.

In the accompanying drawings:

Figure 1 is a view in side elevation, partly in section, of the forward part of a pipe-forming machine illustrating my invention.

Fig. 2 is a plan view of the revolvable mold-carrying table and mold thereon.

Fig. 3 is an enlarged sectional view through the line 3-3 of Fig. 2.

Fig. 4 is a fragmentary top plan view 65 of a detail of said table and mold securing devices.

Fig. 5 is a view in section on line 5-5 of Fig. 4.

Fig. 6 is an underside perspective view 70 of a palette element of the invention.

Referring to said views, in which similar characters of reference indicate like parts in several views, the reference numeral 10 indicates a base serving as a support for the 75 entire pipe-making machine of which the frame-standard 11 thereof is shown. Rigidly mounted upon one end of said base is a circular pedestal 12 upon which a circular table 13 is supported concentrically to rotate in a horizontal plane. A circular bevel-toothed rack 15 is formed or provided upon the underside of said table with which a pinion 16 keyed upon the end of a drive shaft 17 operatively engages to rotate said 80 table in the direction indicated by the arrow in Fig. 2.

Said table has a plane upper surface 18 and is formed with a plurality, preferably 90 four, of inverted T-shaped slots 20 extending radially from the outer periphery of the table to an end wall 21 in proximity to the axis of said table.

A bar 22 is arranged to engage in each 95 said slot and is formed of T-configuration in cross-section with its lateral walls in close sliding fit with the corresponding walls of the slot while its upper face 23 is depressed below the plane of said table and a clearance is provided at 25 between its underside and the bottom of said slot. Each said bar is 100 formed with a plurality of equally spaced tapped holes 26 extending vertically therethrough and each said hole is provided with a screw-threaded plug 27 to close the upper ends thereof against entrance of cement or other foreign matter.

A block, indicated generally by the nu-

meral 30, is provided for each said slot 20 and includes a base 31 of relatively large extent to give stability to the block upon the table. A dependent shallow rib 32 is formed on the underside of said base to engage in said slot 20 and a pair of apertures 33 are formed therethrough to receive lag-screws 35 adapted to enter the respective alternate holes 26 of said bar and thus secure the blocks to the table in rigid adjusted positions. Said apertures are spaced to register with two alternate holes and the rib 32 is of such depth that a space is provided between the underside of the rib 32 and the upper surface 23 of the bar, as indicated in Fig. 5, to ensure the positive clamping of the block upon the table through the T-head 36 of the bar bearing with pressure upon the shoulders 37 of said slots.

20 Each said block includes an integral body 38 having a horizontal shoulder 39 for supporting the mold-base, and is further formed with an integral upstanding portion 40 having an overhanging lip 41 extending in the direction in which the table is rotated.

A pipe-mold is composed of two sections hingedly connected and secured together under tension by a clamp, not shown. 42 indicates the sheet-metal side walls of said mold and 44 the mold-base comprising a vertical collar 45 to which the mold-walls are rigidly secured, an interior beveled ledge 46 and an outer horizontal flange 47 extending outwardly and adapted to be supported on said shoulder 39 of the respective blocks. Integral spaced lugs 48 extend outwardly from the flange 47 to the same number as there are blocks 30 employed on the table and are arranged to extend past the respective portions 40 of the block and to engage under the respective lips 41 thereof so that the mold flange is held securely upon the block against lifting movements and caused to rotate positively therewith through the said lugs being positioned upon the side of the block towards which the table is rotated.

49 indicates an adjustment screw extending through a threaded aperture in said flange adjacent of each said lug 48 to bear centrally of the respective shoulder 39 of the supporting block when the mold is in operative position. Said screws are utilized to level the mold-base upon the blocks in a well understood manner to compensate for wear or distortion of the mold-flange and to maintain the mold-walls at all times in aligned positions. A set-nut 49' may be used to lock said screw in its adjusted position.

A palette 50 consists in a circular metallic plate having an upper plane surface the approximate dimensions of the lower end 65 of the pipe formed thereon and a centrally

positioned opening of the diameter of the bore of the pipe and of the removable core 51 about which the pipe is formed. The outer lower surface of said palette is beveled on the same angle as the ledge 46 of the 70 mold-base upon which it rests when in operative position within the mold. The palette is further provided with a plurality, preferably three, of integral legs 52 evenly spaced on its under side and which support the green pipe when removed from the mold and deposited in the curing chamber.

The mold setting and clamping devices are utilized in a manner substantially as follows: The diameter of the mold-flange 80 47 of the mold of the desired size being ascertained the blocks 30 are arranged at corresponding distances radially from the center of the table to support said mold-flange and to engage the respective lugs 48. 85 The bars 22 in said slots 20 are moved longitudinally to have two of their holes 26 register with the apertures 33 of the block and the screws 35 are employed to secure the block and the bar together and to clamp 90 the latter against the shoulder 37 of the table slots. It will be seen that the blocks 30 may be set in their desired positions and by a small movement of the bars certain holes may be brought to register and the 95 blocks secured as described. The plugs removed to accommodate said screws 35 may then be inserted in the holes from which the screws 35 have previously been taken so that all openings in the bar are closed 100 against entry of cement which might lodge therein and be difficult of removal. Similarly the bar 22 itself fills up the slot against entry of cement material so that the table presents a relatively smooth surface with no 105 crevices for the lodging of cement material and presents no dangerous projections.

When thus properly set the blocks 30 are ready to receive the mold. The upstanding portions 40 delimit an area into which the 110 circular mold-flange 47 is confined and centered so that no manual adjustments are necessary. The operator merely places the mold so that said flange rests upon the shoulders 39 with the lugs 48 in proximity 115 to the respective portions 40 of the blocks so that upon the rotation of the table said lugs will be engaged by said portions 40 and cause the mold to rotate with the table while the overhanging lips 41 will lie over said lugs and retain the mold securely against displacement by tipping or lifting.

The palette is placed in the bottom of the mold when the mold sections are united and form the lower face of the pipe and through the provision of said blocks 30 with supporting shoulders 39 elevated above the table and the legs 52 of said palette elevating the latter to substantially the same plane a space is provided therebelow where 120 125 130

dirt or cement material spilling on the table may accumulate without adversely affecting the set or operative position of the mold as might otherwise be the case if the mold sat 5 directly upon the table.

Furthermore, as the palette is left under the pipe when the latter is removed to the curing room to set it acts as a support and protection therefor and due to its triple legs 10 it will always rest evenly on the floor and support the pipe in erect position regardless of accidental unevennesses therein. Owing to the elevation of the palette upon the legs 52 the mold may be more readily removed and with less danger of injury to 15 the pipe. The clamps holding the pipe mold sections together are loosened and the mold will then drop vertically to the floor the slight distance the mold-base is elevated 20 above the floor by said legs 52 and thereby break the suction between the mold wall and the wet pipe whereupon the mold sections may be taken away without danger to the pipe.

25 Having described my invention, what I claim is:—

1. In a machine of the class described, a rotatable table having a plurality of radially directed slots therein, a bar slidably mounted in each said slot provided with a plurality of tapped holes spaced along its length, and a mold-supporting block provided with means co-operating with said bar-holes for clamping said block 35 to the table.

2. In a machine of the class described, a rotatable table having a plurality of radially directed slots therein, a bar slidably mounted in each said slot provided with a plurality of tapped holes spaced along its length, a mold-supporting block, means to secure said block to said bar, and a screw-threaded plug for closing each of said holes. 40

3. In a machine of the class described, a rotatable table formed with a plurality of radially directed slots, a bar slidably retained in each said slot, and a mold-supporting block detachably connected at spaced intervals to each said bar.

50 4. In a machine of the class described, a rotatable table formed with a radially directed slot, a bar slidably retained in said slot, a mold-supporting block, and means connecting said bar and said block whereby said block may be detachably clamped to the table.

5. The construction such as disclosed where the mold supporting block and the bar are detachably coupled together and are freely slidable longitudinally of the table 60 slot until tightened into place.

6. In a machine of the class described, a rotatable table formed with a plurality of slots, a bar slidably mounted in each said slot to close said slot from the upper face 65 of said table, said bar being formed with a plurality of threaded holes, a block, screw-devices operative in said holes to secure the block to said table and removable means to plug said holes. 70

7. In a machine of the class described, a rotatable table formed with a plurality of radially directed inverted T-shaped slots, a T-shaped bar slidably retained in each said slot, and a mold-supporting block detachably connected at spaced intervals to each 75 said bar.

8. In a machine of the class described, the combination with a rotatable table formed with a plurality of radially directed slots 80 in its upper face, of a block having a rib on its underside interfitting in each said slot, said blocks each having a mold-supporting shoulder and an upstanding portion at its outer edge, said upstanding portion being 85 formed with a laterally directed lip, a mold formed with a lower flange supported on said shoulders and formed with a lug engageable by said lip, and slidable means in said slot to secure said block in adjusted 90 radial positions.

9. In a machine of the class described, the combination with a rotatable table, a plurality of mold-supporting blocks adjustably secured on said table, and a mold having a laterally extending base-flange, of a plurality of screws adapted to protrude through said flange and to bear upon said blocks, respectively. 95

10. In a machine of the class described, 100 a rotatable table having a plurality of radially directed slots therein, a bar slidably mounted in each said slot each provided with a plurality of holes spaced along its length, a supporting block, means to secure said block to said bar by means of said holes, and a plurality of plugs for closing the holes not used. 105

Signed at Portland, Oregon, this 15 day of May, 1923.
